UNITED STATES PATENT OFFICE.

JESSIE E. ACKERMAN, OF PORTLAND, OREGON.

SELF-MARKING DRESS-MARKER.

1,125,790.

Specification of Letters Patent. Patented Jan. 19, 1915.

Application filed March 26, 1913. Serial No. 757,036.

To all whom it may concern:

Be it known that I, JESSIE E. ACKERMAN, a citizen of the United States, residing at Portland, in the county of Multnomah and State of Oregon, have invented a new and useful Self-Marking Dress-Marker, of which the following is a specification.

By way of explanation it may be stated that in marking heights upon garments, and particularly in determining the lengths of skirts, much difficulty has been experienced hitherto, by reason of the fact, that an operator, in addition to the person upon whom the garment is fitted, has been necessary, or, upon the other hand, it has been necessary for the person upon whom the garment is being fitted, to assume a distorted and unnatural posture, in order to manipulate the chalk.

One object of the present invention is to provide a dress marker so constructed that the operator, by a swinging movement of the leg or foot and without stooping or otherwise changing the hang of the garment, may place a mark at the desired height, upon the skirt.

Another object of the invention is to provide a device, which, by a swinging movement of the leg or foot will make upon the skirt, two marks at a fixed height.

The invention aims, further, to provide a marker so constructed that a horizontally swinging support, carrying the chalk holder will be accessible to the operator, without stooping, whereby a horizontal mark may be placed upon any portion of the garment, longitudinally of the same.

It is within the scope of the invention to improve generally, and to increase the utility of, devices of that type to which the present invention appertains.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawing: Figure 1 is a perspective showing the dress marker in operation; Fig. 2 is a perspective of the marker; Fig. 3 shows the marker in horizontal section,

parts being broken away; and Fig. 4 is a vertical section of the chalk holder.

In carrying out the invention there is provided a vertical support which may be of any desired form. In the present instance, the support is mounted to swing horizontally and may be a door, as shown at 1. Although the support 1 may be mounted to swing horizontally, the horizontal swinging feature may be dispensed with, and the support may be fixed. It is essential, primarily, that a support of some sort be provided, along which the mechanism hereinafter described, may be adjusted vertically. In the present instance, there is provided a yoke 2, adapted to be straddled upon the free outer edge of the support, the yoke 2 being provided in its intermediate portion with an extension 3 constituting a brace. Into one arm 4 of the yoke 2 is threaded a wing screw 5, which, at its inner end, may be provided with a swiveled head 6. The head 6 co-operates with the other arm 7 of the yoke 2 and forms a clamp, whereby the yoke may be held in any desired vertical position along the support 1. There is further provided a frame 8, the intermediate portion of which may be attached by rivets 9 or in any other suitable manner to the yoke 2. The frame 8 comprises resilient, diverging arms 10, the arms lying in a common horizontal plane. The arms 10 may be tapered toward their free ends, as indicated at 11.

The arms 10, adjacent their free ends, are provided with chalk holding means. The chalk holding means may be of any desired form. As shown, but not necessarily, each chalk holder comprises a loop 15, inclosing one arm 10, and curved jaws 12 adapted to engage the chalk. A clamp screw 14 is journaled in the arm 10 and in one side of the loop 15, the screw being threaded into the other side of the loop.

In practical operation, the yoke 2 and the frame 8 are positioned at any desired height along the support 1, by manipulating the screw 5. Presupposing that it is desired to mark the length of the skirt, the leg or foot of the operator may be thrust outwardly, to carry a portion of the skirt between the pairs of chalk holders, whereupon, the arms 10 will separate, two marks being made upon the skirt simultaneously, and at a common height.

The device herein disclosed is adapted not only to mark the length of the skirt, but to place marks at any heights upon portions of the garment, other than the skirt. Under 5 such circumstances, the operator may turn her back to the support 1 and reach rearwardly and swing the support 1 horizontally, whereupon one or both of the pieces of chalk will leave a mark upon the back of the 10 garment or elsewhere thereon.

The device, if desired, may include a supplemental frame 25, although this frame 25 is not essential and may be omitted if desired. The frame 25 includes a standard 26 which 15 is vertically adjustable between the intermediate portion of the yoke 2 and the edge of the support 1, the yoke constituting means for holding the standard 26 in adjusted positions. The standard 26 may be provided 20 with an arm 27, similar to the arm 10 and another arm indicated at 28, may or may not be employed. The arm 27 and the arm 28, when used, carry the chalk holders above referred to. The supplemental frame 25 permits 25 the making of three or four marks upon the garment, instead of two marks.

Having thus described the invention, what is claimed is:—

1. A dress marker including yieldably co-

operating arms between which a portion of 30 the dress may be thrust; chalk holders disposed in the same horizontal plane on the arms; and means for supporting the arms.

2. A dress marker comprising a yoke; 35 yieldably coacting arms carried by the yoke; a supplemental frame mounted for adjustment in the yoke and including an arm; chalk holding means on the arms; and means for holding the supplemental frame in adjusted positions with respect to the yoke. 40

3. In a skirt marker, a pair of opposed arms provided adjacent their outer ends with chalk holders, the arms being resili- 45 ent, whereby when a portion of a skirt is thrust between the chalk holders by the leg of an operator, a plurality of marks will be made upon the skirt; and a support engaging means with which the arms are connected, whereby both arms may operate in a common horizontal plane. 50

In testimony that I claim the foregoing as my own, I have hereto affixed my signature in the presence of two witnesses.

JESSIE E. ACKERMAN.
